(57) **CLAIM**

The ornamental design for an insulated case, as shown and described.

DESCRIPTION

FIG. 1 is a front view of an insulated case showing the inventive design.

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a perspective view thereof; and,

FIG. 8 is an alternative perspective view thereof.

The broken lines in the reproductions depict portions of the insulated case that form no part of the claimed design.
